CLAIM

The ornamental design for a support for xylophone/marimba, as shown and described.

DESCRIPTION

FIG. 1 is a perspective view of my support for xylophone/marimba taken generally along one side of the invention, the perspective view from the opposite side being a mirror image thereof;

FIG. 2 is an enlarged perspective view of the components of the design shown disassembled for clarity of illustration;

FIG. 3 is a perspective end view; and,

FIG. 4 is an end view.

1 Claim, 4 Drawing Sheets
